ABSTRACT: A wood pulp and chipping apparatus for cutting and chipping logs into pulpwood comprising a frame with a forward conveyor means and a rear conveyor means disposed to receive logs from said forward conveyor means, and said conveyor means being disposed at an inclined angle with respect to a horizontal plane so as to feed logs carried thereby to a chipping and pulping means comprising an endless chain drive with cutter and chipping teeth thereon, which teeth are disposed in directions so as to cover the top of the endless chain and the opposite sides thereof, and with the chipping and cutting means disposed to receive the logs after they have been fed rearwardly by said rear conveyor means.

SHEET 2 OF 2

FIG. 3.

FIG. 2.

GENERAL E. WOOD

BY

Bearman, Davidson & Bearman
ATTORNEYS.

WOOD PULP AND CHIPPING CHAIN SAW APPARATUS

The present invention relates to an apparatus for producing wood pulp from tree length logs which have been cut from a forest and the like.

It is an object of the present invention to provide a compact and sturdy structure for producing wood chips and wood pulp from full length logs that have been disposed on the apparatus.

It is another object of the present invention to provide a rugged, endless chain device that is disposed at one end of the apparatus of the present invention so that a skipper can roll or place tree logs on the conveyor and will permit the logs to be easily fed into a cutter means disposed on the rear end of the apparatus.

Yet another object of the present invention is to provide a wood pulp device or apparatus comprising a lower forward endless chain conveyor and a rearward endless chain conveyor disposed adjacent the rear end of said first conveyor so as to receive tree lengths or logs therefrom and with a substantially vertically disposed endless cutter conveyor positioned adjacent the rear end of said rearward conveyor to cut or chip the log fed to the cutter conveyor so as to produce wood pulp therefrom.

Yet another object of the present invention is to provide a novel and compact wood pulp device for chipping a log into wood pulp which device is provided with cutter means on an endless conveyor means, which conveyor means are disposed as to chip into or cut into the wood in three different directions disposed perpendicular to each other to produce an efficient chipping and cutting result.

Various other objects and advantages of the present invention will be readily apparent from the following detailed description, when considered in connection with the accompanying drawings forming a part thereof, and in which:

FIG. 1 is a top plan view of the wood pulp apparatus embodying the present invention;

FIG. 2 is a section taken along the lines 2-2 of FIG. 1, illustrating the device in side elevation;

FIG. 3 is a section taken along the lines 3-3 of FIG. 2 illustrating a front view of the apparatus embodying the present invention;

FIG. 4 is an enlarged detailed view illustrating the cutting teeth embodied in the cutting means of the present apparatus; and

FIG. 5 is a section taken along the lines 4-4 illustrating the positions of the different cutting teeth on the cutting means of the present invention.

Referring to the drawings, the reference numeral 10 generally designates the chipping and wood pulping device or apparatus of the present invention, provided with a frame including a bottom 12, a forward sloping rear wall 14, and opposite side walls 16.

Disposed within the frame and adjacent the rear wall 14 thereof is an endless cutter or chipper conveyor means 18. The cutter means is provided with a plurality of laterally spaced, endless chains 20, which chains are disposed on or carried by sprocket wheels 22 and 24. The FIG. 2 shows that the sprocket wheel 22 is disposed above and forwardly of the lower sprocket wheel 24 so that the endless chain 20 extends in a substantially vertical direction with its upper end disposed forwardly of its rear end.

The lower sprocket wheels 24 are disposed on a shaft 26, which shaft is connected to the coupling of an electric motor 28 for operation thereby. The shaft 26 is disposed in suitable well known bearings. The upper sprocket wheels 22 are secured to a shaft 30 also disposed in conventional bearings and driven through the chains 20 connected to the drive sprocket wheels 24. The endless chains 20 are connected to the motor 28 so as to be driven in the direction indicated by the arrow shown in FIG. 2 with the forward portion of the endless chain 20 moving in a downward direction and the rear portion moving in an upward direction.

The apparatus is provided with a rearward log conveyor endless chain means generally designated 32 which is pro-

vided with three laterally spaced endless chains 34 disposed between the cutter endless chains 20, as best seen in FIG. 1.

The endless chains 34 are carried by a rear sprocket wheel 36, as best seen in FIG. 2, and a forward sprocket wheel 38 with the rearward sprocket wheels 36 being disposed above the forward sprocket wheels 38, and with the rearward sprocket wheels 36 being disposed between the endless chains 20. The sprocket wheels 36 are secured to a shaft 40 while the sprocket wheels 38 are secured to a shaft 42.

10 The frame is provided with a reduction gear train mechanism generally indicated at 44 adjacent the wall 16 of the frame which is on the opposite side of the frame from the electric motor 28. The reduction gear train mechanism is of conventional and well known construction and provides a drive from the drive shaft 26 to the upper shaft 40 of the rearward log conveyor endless chain means 32. The sprocket wheels 38 disposed on shaft 42 are driven by carrying the endless chains 34 thereon, which chains 34 are driven by the sprocket wheels 36. The reduction train gear mechanism greatly reduces the speed of the chains 34, with respect to the cutting chains 20, which travel much faster and the chains 34 are driven in the direction indicated by the arrows in 34 with the upper portion of the chain 34 moving toward the rear of the apparatus and the lower portion of the chains 34 moving toward the front of the apparatus.

The chains 34 are provided with angle irons 46 secured thereto at spaced intervals so as to push or move the log, indicated at 48, upwardly along the conveyor and into the cutter conveyor chains 20.

30 The apparatus is provided with a lower forward endless log conveyor means 52 with a plurality of laterally spaced endless chains 54 having their rearward ends disposed between the forward ends of the endless chains 34 as best seen in FIG. 1. The endless chains 54 are provided with a plurality of transversely extending angle irons 56 disposed thereon at spaced intervals similar to the angle irons 46, so as to push or move the logs 48 toward the conveyor means 32.

The endless chains 54 are carried by identical sprocket wheels designated 38', the same as sprocket wheels 38, secured to shaft 42 between the sprocket wheels 38 of the endless chains 34. The forward ends of the chains 54 are carried by sprocket wheels 58 of much smaller diameter than the sprocket wheels 38', as best seen in FIG. 2. The sprocket wheels 58 are disposed on a shaft 60 and driven through the connection of the rear end of the endless chains 54 to the sprocket wheels 38' on the shaft 42. The small sprocket wheels 58 are provided so that the forward end of the endless conveyor chains 54 are disposed at a low enough level so that a skipper can easily roll or move the logs 48 on the front end of the conveyor to pass it to the rear conveyor and feed it into the cutter conveyor means. The forward shaft 60 is supported by a plurality of forwardly extending bracket or structural support members 62 and feet 64, as best seen in FIG. 2.

55 Referring to the FIGS. 4 and 5, it is to be noted that the endless chains 20 which comprise the chains for the cutter conveyance means 18 are provided with cutter teeth thereon. The cutter teeth are provided on the endless chain 20 with a first tooth 66 secured to one side of the chain 20 and having an upwardly and horizontally extending cutter blade 68 thereon, with a cutting edge 70 on the front thereof. The blade 68 completely extends across the width of the chain 20.

The chain is provided with another cutter tooth 72 thereon which is secured to the opposite side of the chain 20 from the tooth 66, and with an upwardly extending portion 74 and a horizontal cutting blade 76 thereon with a forward cutting edge 78.

70 The next link of the chain 20 is provided with a tooth 80 thereon which is secured to the same side of the chain 20 as the tooth 72. The cutter blade 82 and the cutting edge 84 of the tooth 80 are disposed on the same side of the chain 20 as the tooth 66.

75 Disposed on the next link of the chain 20 is another cutter tooth 86 secured to the same side of the chain as the tooth 66 and with a horizontal extending portion 88 and a downwardly

extending portion of cutter blade 90 with a cutting edge 92 thereon. The blade 92 is disposed on the side of the chain 20 opposite the side upon which the cutting blade 82 of the tooth 80 is disposed on. This is sequential arrangement of the teeth on the cutter blade throughout the entire length of the endless chains 20. Thus, the cutting teeth on the chains 20 reach to the next corner of the chain from its initial or original edge. These cutting chains are designed to be turning at a very fast rate of speed and the feed chain moves very slowly. The teeth completely encircle the chains 20 with the exception of the rear of the chain 20 or the part that is disposed adjacent the sprocket wheels. This arrangement of the teeth with two teeth on top and two teeth on the sides enables the chains 20 with their teeth to cut through a log even in a pinching condition.

In operation, the log is disposed on the front end of the forward log conveying means 52 and the transversely extending angle irons 56 cause the log to move to the rear of the apparatus and onto the front end of the lower log conveyor means 52. The operation of the apparatus and the gear chain causes this forward conveyor to again move the logs 48 toward the rear of the apparatus and into the cutting teeth 66, 72, 80 and 86, arranged in sequence throughout the periphery of the chains 20. These cutting teeth cause the logs to be chipped.

Additional changes can be made in the present invention without changing the relative location or arrangement of the various parts of the invention, therefore the present invention is shown through the appended claims:

I claim:

1. An apparatus for producing wood pulp from logs and the like, comprising a frame, a conveyor means carried by said frame, a cutter means disposed adjacent the rear of said conveyor means for receiving material therefrom, cutting teeth on said cutter means for pulping material delivered thereto and means for driving said conveyor and cutter means, wherein said conveyor means comprises endless chains with transverse pusher members disposed on sprocket wheels and with its rear end disposed above its forward end, and wherein said cutter mean is a plurality of laterally spaced

endless cutter chains disposed between the rear portions of said conveyor endless chains and having upper supporting sprocket wheels spaced above the conveyor means and lower supporting sprocket wheels spaced below said conveyor

- 5 means, said cutter chains having a plurality of cutter teeth, wherein one type of cutter tooth on said cutter chains has a side vertical portion secured to one side of said chains and a horizontal portion with a front cutter edge extending across the associated chain and beyond its opposite side, wherein
10 another type of cutter tooth on said cutter chains is identical to said one type tooth and oppositely disposed thereon, and wherein a third type of tooth has a vertical side portion, a horizontal top portion and a second downwardly extending cutter portion disposed on the side of its associated chain
15 opposite said vertical portion.

2. The apparatus of claim 1 wherein a fourth tooth is provided on said chain identical to said third type tooth and oppositely disposed.

- 20 3. The apparatus of claim 2 wherein said one, said another, said third and said fourth type tooth are disposed in said sequence on said chain.

4. The apparatus of claim 1, and wherein the upper supporting sprocket wheels are spaced forwardly from the lower
25 supporting sprocket wheels, whereby said laterally spaced cutter chains are inclined downwardly and rearwardly.

5. The apparatus of claim 4, and wherein said conveyor means comprises first endless conveyor chain means disposed on sprocket wheels carried by the frame with its rear end disposed above its forward end, second endless conveyor chain means disposed rearwardly of said first conveyor chain means to receive material therefrom, said second conveyor chain means comprising a plurality of laterally spaced endless chains with transverse pusher members carried by rear sprocket wheels and forward sprocket wheels disposed on the same shaft as the rear sprocket wheels carrying the first conveyor means endless chains and with the rear sprocket wheels of the second endless chain means disposed at a higher vertical level than the
30 front sprocket wheels of said second conveyor chain means.
